(57) **CLAIM**

The ornamental design for a welding switch cover as shown and described.

DESCRIPTION

FIG. 1 is a front perspective view of a welding switch cover showing my new design and an exemplary application thereof;

FIG. 2 is another front perspective view thereof;

FIG. 3 is a right view thereof;

FIG. 4 is a left view thereof;

FIG. 5 is a front view thereof;

FIG. 6 is a back view thereof;

FIG. 7 is a top view thereof;

FIG. 8 is a bottom view thereof; and,

FIG. 9 is another front perspective view thereof.

The broken lines included in the Figures illustrate parts of the article and form no part of the claimed design.
